LOOSE POWDER COMPACT

Filed Sept. 4, 1928

Inventor

James Leslie Younghusband

Charles O. McVay

UNITED STATES PATENT OFFICE

JAMES LESLIE YOUNGHUSBAND, OF CHICAGO, ILLINOIS

LOOSE-POWDER COMPACT

Application filed September 4, 1928. Serial No. 303,637.

This invention relates to a compact for loose powder in which the powder compartment is included between the bottom of a receptacle and an annular flange frictionally retained within said receptacle, which flange also provides an opening to said compartment, the flange member having a bead thereabove, the bead and flange being formed from a piece of sheet metal, and an applicator secured between the flange and bead serving as a stopper for the opening to the powder compartment.

An object of the invention is to provide a compact for loose powder having a flanged opening with which an applicator cooperates to form a closure for the powder compartment.

Another object is to provide a loose powder compact having a flanged opening, which flange is defined by a member made from a single sheet of metal forming the flange as well as a bead above the flange and having the free ends thereof extending outwardly to frictionally engage the walls of the receptacle.

Another object of the invention is to provide a metallic double flange member for compacts in which the inner margins of the openings defined by the flanges are curved in transverse section for providing smooth margins.

A further object is to provide a flange structure for compacts which may be economically manufactured.

The above, other and further objects will be apparent from the following description, accompanying drawings and appended claims.

According to the invention, the compact comprises a receptacle with which is associated in frictional engagement a flange member made from a single piece of sheet metal so bent and shaped as to form an inwardly directed flange serving as the top of the powder compartment and defining the opening thereto, together with a bead spaced above said flange with the free ends of the member extending outwardly to frictionally engage the wall of the receptacle.

One form of the invention is shown in the

accompanying drawings and the views thereof are as follows:

Figure 1 is a front elevational view of a compact embodying the invention, showing the same partially opened. 55

Figure 2 is a top plan view of a compact fully opened.

Figure 3 is an enlarged vertical section through the center of the powder receptacle.

The compact chosen to illustrate the invention comprises a bottom member 1 and a top member 2 hinged at 3. I do not wish to be limited to the hinge construction shown as I contemplate a compact in which the top and bottom members are separate. 60 65

The bottom or receptacle 1 may be made of metal, bakelite, ivory, or other suitable material, and as illustrated comprises a dished bottom 4 with an integral circular wall 5, the upper margin of which is shouldered at 6 to receive the top 2. The flange member made of sheet metal is bent to provide an inwardly directed horizontally disposed flange 7 and a bead 8 thereabove of greater diameter. The free ends 9 and 10 are directed outwardly, the 70 75 ends 9 frictionally engaging the inner surface of the wall 5 above the bottom of the receptacle forming the powder compartment 11, the opening in the flange 7 serving as a means of access to the powder.

The free margin 10 of the member is shown as overlying the top edge of the wall 5. However, this margin might frictionally engage the inner surface of said wall if desired. 80

An applicator or powder puff 12 is retained between the bead 8 and the flange 7 by being sprung past said bead by which it is held against the flange 7 in position to close the opening to the powder compartment. 85 90

The top 2 may have a mirror 13 retained in position by a ring 14. The projection 15 is formed on the top 2 to aid in opening the top when closed.

While I have described more or less precisely the details of construction of my invention, yet I do not wish to be limited thereto as I am aware that changes may be made in the arrangement and proportion of parts and that equivalents may be substituted, all with- 95 100

out departing from the spirit and scope of my invention.

I claim as my invention:

1. A compact for loose powder comprising a receptacle for containing the powder, a flange member frictionally retained within said receptacle, said flange member being made of a strip of sheet metal shaped to provide a substantially horizontal flange and a bead overhanging said flange in spaced relation, and an applicator retained in the opening of said flange by spring engagement with said bead.
2. A loose powder compact comprising a powder receptacle, a spring ring shaped to provide a substantially horizontal annular inwardly directed flange and an inwardly directed bead above said flange, said bead defining an opening of greater diameter than the opening defined by said flange, and an applicator retained in said flanged opening by engagement with said bead.
3. A loose powder compact comprising a receptacle having a flanged opening therein, the flange defining said opening comprising a retaining ring formed with a substantially horizontal annular flange extending inwardly and a bead integral with said ring above said flange, and an applicator arranged to close the opening in said flange by frictional engagement with said bead.
4. A loose powder compact comprising a receptacle having a flanged opening therein, said flange being formed from a metal ring frictionally retained in said receptacle and formed with a bead above the flange and an applicator arranged to engage the flange surrounding the opening and to be retained in position to close said opening by engagement with a bead.
5. A compact for loose powder comprising a receptacle having a flanged opening, the flange defining said opening comprising a ring bent to provide a flange and a bead, with the bead arranged above the flange and frictionally retained within the receptacle, and an applicator retained between said flange and said bead by friction.
6. A loose powder compact comprising a receptacle having a flanged opening therein, the flange defining said opening consisting of a metallic ring formed from a single piece of sheet metal, said flange being formed by bending said sheet metal forwardly in open ended loops with the free margins of said metal extending outwardly and frictionally engaging the wall of the receptacle, a bead being formed in said member above said flange, and an applicator retained in position between said flange and said bead to close the opening in said flange.

In testimony whereof I have hereunto subscribed my name at Chicago, Cook County, Illinois.

James Leslie Younghusband.
